A. SMALLWOOD.
FURNACE FOR HEAT TREATMENT.
APPLICATION FILED SEPT. 19, 1916.

1,290,384.

Patented Jan. 7, 1919.

Inventor:-
Alfred Smallwood,
By:- B. Amigo
Atty.

UNITED STATES PATENT OFFICE.

ALFRED SMALLWOOD, OF LONDON, ENGLAND.

FURNACE FOR HEAT TREATMENT.

1,290,384.

Specification of Letters Patent.

Patented Jan. 7, 1919.

Application filed September 19, 1916. Serial No. 121,075.

To all whom it may concern:

Be it known that I, ALFRED SMALLWOOD, a subject of the Kingdom of Great Britain, residing at 42 Hargrave Park, Highgate, 5 London, N., in the county of Middlesex, England, have invented certain new and useful Improvements in or Relating to Furnaces for Heat Treatment, of which the following is a specification.

10 This invention comprises certain improvements in or relating to furnaces for heating, hardening, tempering, annealing, carbonizing and other processes.

According to the present invention an oil 15 or other bath is adapted to be disposed in such relationship to the heating chamber as to permit of the goods being removed from the heating chamber into the oil or other bath without being exposed to the atmosphere during such removal.

20 The oil or other bath may be adapted to be moved laterally and when in position for receiving the goods from the heating chamber sealing means are provided for sealing the means of communication with the oil 25 or other bath from the atmosphere.

In order that this invention may be clearly understood and readily carried into practice, reference may be had to the appended 30 explanatory sheets of drawings, upon which:—

The figure is a sectional elevation of my invention.

According to my invention I provide a 35 furnace with a vertically disposed heating chamber, the bottom of which is closed by a bung adapted to be removed in such a manner as to permit of the goods being lowered from the heating chamber into an oil 40 or other bath, as for instance for tempering purposes.

The bung is adapted to be readily removable and is conveniently of a character sufficiently substantial to take the weight of the 45 goods, which latter are advantageously suspended in the heating chamber, but may have to rest upon the bung.

With this object in view the bung *r* may be carried by a truck *s* adapted to be moved 50 laterally or horizontally on rails *t*.

The rails *t* are adapted to be raised and lowered, as for instance by being mounted with links *u*, *u* to be displaced by a parallel motion, the links being operated in any suitable manner, as for instance by a worm *v*

engaging with a quadrant *w* fixed coaxially with one of the links *u*.

Between the bung *r* and the lower extremity of the heating chamber, a sand or other seal *x* is incorporated, and in separating the bung from the heating chamber it is first necessary to lower the bung to withdraw the latter from the lower part of the heating chamber and also to separate the sand or other seal *x*, after which the carriage *s* carrying the bung is disposed laterally along the rails *t* by any approved mechanism. Guides *z* are provided to maintain the bung *r* and carriage *s* in central relationship to the heating chamber *a* during its vertical displacement, by virtue of their engaging any suitable fixed member.

Below the level at which the carriage works a tank *2* is incorporated so that after the removal of the bung by the carriage, the goods contained in the heating chamber can be lowered into the tank, which may, for instance, contain oil. The bung operating mechanism is contained in a space which is sealed from the atmosphere, and the opening in this space permitting of access to the tank is adapted to be sealed. For this purpose a sealing member *3* in the nature of a cylinder having near its upper edge one portion *4* of an annular sealing device 85 adapted to coöperate with the other portion *5* of such sealing device provided around the outlet offering access to the tank *2*, is adapted to be lowered into the tank in such a manner that when the sealing parts *4*, *5*, are in 90 coöperation, the lower part of the cylinder *3* dips below the surface of liquid in the tank, and thereby effectively closes the space containing the bung operating mechanism from the space containing the tank and 95 therefore from the atmosphere, while permitting of access to the contents of the tank.

The tank is contained in a pit and is adapted to be moved laterally, as for instance by being provided with anti-friction members 100 adapted to work upon runners. Two or more tanks may be provided in the pit for alternative use, and lateral displacement of the tank or tanks is permitted by the cylindrical sealing member *3*, which may be 105 raised clear of the upper surface or edge of the tank *2* to permit of the lateral displacement of the latter. Suitable guiding means *7* are provided for guiding the sealing member *3* in its vertical movements, 110

and such movements may be imparted to said sealing member 3 by any suitable mechanism, such as a cord 8 carried around suitably disposed pulleys to a point for convenient operation.

The tank for containing oil may have a hollow wall 6 which may contain water for cooling purposes.

It will of course be understood that when 10 the bung is removed from under the article, the latter is supported by a crane by means of a suitable holding device passing into the top of the furnace chamber. It is by this means that the article is lowered into the 15 oil bath.

What I claim as my invention and desire to secure by Letters Patent is:—

A furnace, having a vertically disposed elongated heating chamber, a bung for the lower extremity thereof, mechanism for 20 closing and unclosing said bung or closure member, said mechanism being contained within an inclosed space, an oil or other bath disposed below said space, and means for sealing the opening offering communication with the oil or other bath.

In witness whereof I have hereunto set my hand.

ALFRED SMALLWOOD.
